Primary Examiner — Mark A Goodwin*(74) Attorney, Agent, or Firm* — The Webb Law Firm(57) **CLAIM**

The ornamental design for a control and indicator unit for a forklift, as shown and described.

DESCRIPTION

FIG. 1 is a front perspective view of an embodiment of a control and indicator unit for a forklift in accordance with the present design;

FIG. 2 is a front elevation view thereof;

FIG. 3 is a left side elevation view thereof;

FIG. 4 is a rear elevation view thereof;

FIG. 5 is a right side elevation view thereof;

FIG. 6 is a top plan view thereof; and,

FIG. 7 is a bottom plan view thereof.

The broken lines shown in FIGS. 3-7 depict other components of the control and indicator unit are included for environmental purposes only and forms no part of the claimed design.
